UNITED STATES PATENT OFFICE.

CHARLES T. BAILEY AND HARRY B. WILSON, OF TAMPA, FLORIDA.

WINDOW-SHADE HOLDER.

1,407,624.

Specification of Letters Patent. Patented Feb. 21, 1922.

Application filed June 19, 1920. Serial No. 390,156.

To all whom it may concern:

Be it known that we, CHARLES T. BAILEY and HARRY B. WILSON, citizens of the United States, residing at Tampa, in the county of Hillsborough and State of Florida, have invented new and useful Improvements in Window-Shade Holders, of which the following is a specification.

Our present invention has reference to suspending and operating means for window shades.

Our improvement is especially adapted for use in connection with inverted shades and our primary object is the provision of simple, cheap and thoroughly efficient means for actuating the shade and for sustaining the same at varying adjustments.

In carrying out our invention, we propose to arrange on the sides of a window casing vertically disposed wire or rod members which are guided through the respective edges of a shade, the latter being supported on a spring influenced roller and having at its opposite or free end a combined lift and actuating lever mechanism and spring influenced dogs which engage with the respective wires or rods for preventing the free winding or unwinding of the shade and for holding the latter at different adjustments.

It is also our purpose to produce a shade attachment and actuating means which shall be of a simple construction, easily attached to the shade and to the window casing, easily operated, thoroughly efficient in operation, and one which can be arranged upon any size of window casing or shade.

We accomplish the foregoing objects, and others which will appear as the nature of the invention is better understood, by a construction, combination and operative arrangement of parts, a satisfactory embodiment of which being illustrated by the drawings.

In the drawings:

Figure 1 is a front elevation of a window casing having an inverted shade thereon and illustrating the application of our improvement.

Figure 2 is an edge view, the casing being in section.

Figure 3 is a rear elevation on an enlarged scale, parts being in section.

Figure 4 is a sectional view on the line 4—4 of Figure 3.

Figure 5 is a sectional view approximately on the line 5—5 of Figure 3.

Figure 6 is a sectional view on the line 6—6 of Figure 3.

In the drawings, a window casing is indicated by the numeral 1. To the vertical members or the trim of the casing, slightly above the stool thereof we attach brackets 2 and 3 respectively on which the pintles of the spring influenced roller 4 for the shade 5 are supported. The brackets 2 and 3 are substantially of the ordinary construction, one being provided with a round opening and the other with a rectangular opening receiving the respective round and rectangular pintles of the roller. Each of the brackets 2 and 3, however, have their attaching plate, adjacent to the upper ends thereof provided with outwardly extending lugs 6.

On the vertical members or trim of the casing 1, in a line with the brackets 2 and 3, and at any desired height with respect to the casing, there are secured substantially U-shaped members 7. These members 7 are secured to the casing by headed wood screws 8 passing therethrough and entering the casing. The screws are arranged in a line with the lugs of the respective brackets 2 and 3. The lugs 6 have round depressions therein to receive the looped ends of wire or rod members 10. The upper ends of these rods or wires 10 are coiled around the shank of the screws 8 and are contacted by the heads of the said screws, so that the said rods or wires are thus sustained in a taut condition.

The shade 5 is arranged outward, but is designed to contact with the rods or wires 10. The shade has its outer end provided with the usual stitched fold through which passes the ordinary wooden slat 11. To the ends of the slat, on the inner face of the shade we secure metallic plates or housings 12. The plates have their outer edges rounded upon themselves, as at 13, and through these rounded portions the rods or wires 10 pass. The plates or housings 12 have their upper edges provided with spaced ears 14 that overlie the outer edge of the shade, and the plates or housings 12 are secured to the shade and its slat 11 by a bolt member 15 that is engaged by a nut 16. On the ends of the rounded portion of the respective plates or housings 12 are formed inwardly projecting elements in the nature of ears 17 and 18 respectively. Pivotally secured, as at 19, to the upper ear of the respective plates or housings 12 is a dog

20. This dog has its active face rounded, as at 21 and is provided with a curved body portion 22. The body has its end terminating in the plate or housing opposite the 5 lower ear 18 thereof, and the said end is preferably widened and rounded and has an opening therethrough. Through this opening and through a suitable opening in the lower ear 18 of each of the plates or 10 housings pass the ends of a helical spring 23. The springs exerting a tension upon the body or tail portions of the dogs swing the active rounded faces thereof in contacting engagement with the rods or wires 11, forcing the latter into frictional engagement with the rounded ends of the plates or housings 12, and thus locking the shade on the rods or wires.

To the slat 11, centrally at the outer end 20 of the shade we bolt, as at 24, to the cross sectionally U-shaped body member 25 of the shade, an actuating member or lift 26. The lip of the lift is arranged over the outer face of the shade above the outer edge thereof.

25 The inner plate of the body 25 has its lower edge rounded over itself, and the ends of the said rounded portion are extended to provide ears 27. Pivoted, as at 28 to the respective ears 27 is the body portion 29 of a 30 lever 30. Each of the levers has its outer end arranged at an angle with respect to its body. The levers being constructed of strips of metal are given a half turn at the outer portions thereof and the finger pieces 31 of 35 the said outer ends of the levers are rounded.

The body portion of each of the levers has its outer edge provided with an angle ear 32 that has a threaded opening therethrough for the reception of an eye bolt 33. Connected to each of the eye bolts and to the 40 ends of the tail portions of the dogs, preferably at the points where the springs 23 are secured to the said dogs, are cables 34.

It will be apparent that by exerting a pressure 45 on the finger pieces of the levers 30, the latter will be swung toward the center, and the dogs will be brought out of engagement with the rods or wires, 10 permitting the shade to be vertically adjusted on the

casing. The middle finger of the operator 50 is arranged beneath the rounded surface of the lift 26, while his forefinger and thumb engage the finger pieces 31. Thus the operator has control of the curtain in both the raising and lowering thereof, and by merely 55 releasing pressure on the finger pieces 31 the dogs will again spring into engagement with the wires to prevent the spring wound roller from further influencing the curtain.

Having thus described the invention, 60 what we claim, is:—

1. In combination with a window casing and a spring wound shade thereon, of guides carried by said casing, plates respectively secured to the corners of the free end of 65 said shade and provided with curved outer edges surrounding said guides, spaced ears extending from said curved outer edges, curved spring influenced dogs pivotally secured to two of said ears and engaging said 70 guides and means for actuating said dogs.

2. In combination with a window casing and a spring wound shade thereon, of a pair of vertical guide rods secured to said casing, plates respectively secured to the corners of 75 the free end of said shade and provided with curved outer edges engaging said guide rods, an ear extending from each of said curved outer edges, a spring influenced dog pivotally secured to each ear and normally engaging the respective guide, and means for disengaging said dogs from said guides.

3. In combination with a window casing and a spring wound shade thereon, of guides carried by said casing, plates respectively 85 secured to the corners of the free end of said shade and provided with curved outer edges surrounding said guides, an ear extending from each of curved outer edges, a spring influenced dog pivotally secured to 90 each ear, a lever operated means normally engaging the respective guide for disengaging said dogs from said guides.

In testimony whereof we affix our signatures.

CHARLES T. BAILEY.
HARRY B. WILSON.
